(57) **CLAIM**

The ornamental design for a table, as shown and described.

DESCRIPTION

FIG. 1 is a front perspective view of a first embodiment of a table showing my new design;

FIG. 2 is a front view thereof;
FIG. 3 is a rear view thereof;
FIG. 4 is a right side view thereof;
FIG. 5 is a left side view thereof;
FIG. 6 is a top view thereof;
FIG. 7 is a front perspective view of a second embodiment of a table showing my new design;
FIG. 8 is a front view thereof;
FIG. 9 is a rear view thereof;
FIG. 10 is a right side view thereof;
FIG. 11 is a left side view thereof;
FIG. 12 is a top view thereof;
FIG. 13 is a front perspective view of a third embodiment of a table showing my new design;
FIG. 14 is a front view thereof;
FIG. 15 is a rear view thereof;
FIG. 16 is a left side view thereof;
FIG. 17 is a right side view thereof;
FIG. 18 is a top view thereof;
FIG. 19 is a front perspective view of a fourth embodiment of a table showing my new design;

FIG. 20 is a rear view thereof;
FIG. 21 is a front view thereof;
FIG. 22 is a right side view thereof;
FIG. 23 is a left side view thereof; and,
FIG. 24 is a top view thereof.
The broken lines shown in FIGS. 1-24 illustrate portions of the table that form no part of the claimed design. In the embodiments shown in FIGS. 1-6 and 7-12, the shading on the upper shelf is intended to indicate a transparent or translucent material, and the shading on the lower shelf is intended to indicate an opaque material. In the embodiments shown in FIGS. 13-18 and 19-24, the shading on both the upper shelf and the lower shelf is intended to indicate a transparent or translucent material. The bottom views are omitted and form no part of the claimed design.
